DISTILLATION OF TAR

Filed April 12, 1929

UNITED STATES PATENT OFFICE

STUART PARMELEE MILLER, OF ENGLEWOOD, NEW JERSEY, ASSIGNOR TO THE BARRETT COMPANY, OF NEW YORK, N. Y., A CORPORATION OF NEW JERSEY

DISTILLATION OF TAR.

Application filed April 12, 1929. Serial No. 354,477.

This invention relates to a new and improved method of preparing tarry oil and embraces both the method and apparatus.

According to the present invention hot coke oven gases or gas retort gases carrying suspended heavy tar and pitch constituents are employed for distilling tar, and the resulting gases enriched in condensable constituents and carrying a reduced per cent of entrained impurities based on the condensable vapor content of the gases, are combined with hot coke oven gases or gas retort gases not so treated, and the combined gases are cooled to condense tarry oils of desired quality and character therefrom.

According to the present invention I employ coke oven or gas retort gases at an elevated temperature preferably at a temperature approaching the temperature of the gases as they leave the ovens or retorts for the distillation of tar, which may be a heavier tar or a tarry oil or even a low or medium melting point pitch. By this distillation the condensable vapor content of the gases is increased. This enrichment of the gases in condensable constituents reduces the per cent of entrained impurities carried by the gases based upon the condensable vapor content of the gases, so that on cooling an oil is obtained which has a relatively low free carbon content. If the distillation is effected by spraying the gases with the tar, the spray of tar scrubs entrained impurities from the gases to a greater or less extent. The enrichment may be accomplished by an intense spray of the tar which simultaneously enriches the gases and de-tars them, removing substantially all of the entrained impurities from the gases, or the gases may be scrubbed to a lesser extent.

The resulting gases which are enriched in condensable constituents are blended with ordinary gases not so cleaned and the distillation and scrubbing are so regulated and co-ordinated with the blending operation that the tarry oil produced on subsequent cooling of the combined gases, which may be fractional cooling, is a tarry oil with a low free carbon content and having other desired characteristics.

The free carbon content of the tarry oil produced may be such that the oil as a whole, and the oil even after distillation to remove any excess of low boiling point constituents, will have a sufficiently low content of so-called free carbon to enable it to be directly employed without the addition of distillate oil for making creosoting compositions. If the content of tarry matter as evidenced by the content of so-called free carbon is not sufficient in the tarry oil recovered, additional tar may be blended therewith.

In making the so called coal tar solutions which are used commercially for creosoting, the greater part of the tar collected from the coke oven gases is distilled and the distillate is blended with a relatively small proportion of undistilled tar usually in the proportions of 80 parts of distillate to 20 parts of tar or less to make the coal tar solutions of commerce. The distillation of this large amount of tar is expensive and when distilled by the usual methods considerable decomposition of oil takes place during the distillation with resulting loss of valuable oil and corresponding increase in pitch production. When creosoting composition is made according to this invention, the losses due to decomposition are lessened or substantially entirely obviated, and operating expenses may be reduced.

With slight alterations an ordinary coke oven plant, for example, may be adapted for carrying out this invention. For example, in a coke oven battery of sixty ovens, with three gas collector mains, each connected with twenty ovens, one or two of the collector mains may be equipped for distilling tar. By blending the resulting enriched gases with the balance of the gases which have not been enriched by the distillation of tar therein, and cooling the combined gases to separate tarry oil, a tarry oil of low carbon content will be produced.

The tar distilled may be ordinary coke oven tar, which is a blend of various tars obtained in the ordinary operation of a coke oven battery. The heavier tar alone may be distilled, or lighter tar or tarry oils may be distilled. Tar from other sources may be

distilled, for example, gas house tar, water gas tar, etc. By proper selection of the tar distilled, by regulating the extent to which the distillation is carried, by regulating the amount of enriched gases blended with un-enriched gases, by regulating the cooling of the blended gases to separate one or more fractions, etc., tarry oil products meeting different specifications may be produced.

10 The extent to which that portion of the gases employed for distillation is enriched depends upon the temperature of the gases, the nature of the contact effected between the tar and the gases and the length of time 15 during which they are in contact. The extent to which impurities are removed from these gases is likewise dependent upon the nature and degree of the contact between the tar and the gases. For example, such 20 an intense spray of tar may be produced in the gases that the gases will be thoroughly scrubbed and substantially de-tarred during the distillation. Such a spray may be thrown into the gases from a rapidly rotating 25 roll which dips to but a slight extent into a body of the material to be distilled. The tar may be sprayed into the gases again and again by this means, and the extent to which the distillation is carried thus regulated. A less intense spray may be produced 30 by nozzles, or paddles, where such thorough spraying of the gases is not contemplated.

The boiling range of the vaporized oils in the gases leaving the collector main in which 35 distillation occurs, and hence the boiling range of the oils separated from these gases in the coolers, is dependent upon the temperature at which the gases leave the collector main. This is controlled by controlling 40 the distillation in the main. Where the temperature of the gases is too high it may further be controlled by cooling the gases in the main by spraying them to a limited extent with water or ammonia liquor, or mixing 45 a limited amount of water or ammonia liquor with the tar distilled. The distillation may be in part controlled by this means.

The boiling range of the oils separated 50 from the gases not employed for distillation may similarly be controlled by regulating the extent to which they are cooled in the collector main in which they are collected.

The tar to be distilled may be brought 55 into intimate contact with the hot gases by admitting the tar into the gases thru sprays, or by maintaining a body of tar and partially distilled tar in the bottom of the collector main and spraying this up into the gases by suitable spraying means so that 60 the tar is brought repeatedly into intimate contact with the hot gases passing thru the collector main and thereby distilled. Fresh tar may be continuously added to this body of tar, and finished pitch continuously with- 65 drawn therefrom.

The distillation is advantageously carried out with the gases at a high temperature, approximately that at which they leave the ovens or retorts, and the tar may be distilled to pitch of a relatively high melting point, for example, 250° F., or 300° F. or higher. The distillation of the tar to such a high melting point pitch increases the per cent of higher boiling oils carried as vapors by the gases and the condensation of such higher boiling oils and their separation from the gases in the condensers produces a tarry oil containing such high boiling oils.

The invention will be further described in connection with the accompanying drawing 80 which shows in a more or less conventional and diagrammatic manner an arrangement of apparatus suitable for carrying out the improved process at a coke oven plant.

Fig. 1 is a plan view of a coke oven battery 85 equipped with 3 gas collector mains equipped for the carrying out of this invention;

Fig. 2 is a detail showing a section thru 90 one of these mains;

Fig. 3 shows means which may be employed for supporting the shaft 24 in the collector main; and

Figs. 4 and 5 show modified agitating 95 means.

A battery of coke ovens 5 is shown as being equipped with three collector mains 6, 7 and 8. The ovens are connected with the collector mains thru uptake pipes 9. The collector mains are connected with 100 cross-over mains 10, 11 and 12. The cross-over mains are connected with condensers 13. An exhauster 14 is employed for drawing the gases thru the system.

The two collector mains 7 and 8 are 105 equipped with the usual gas cooling means which may be ammonia liquor sprays and the condensate thrown down in these collector mains by the cooling of the gases is collected in the decanters 15 and 16. One heavy 110 tar tank 17 is shown for collecting the tar from each of these decanters. The tarry oil from the condensers is drawn off into the decanter 18, together with ammonia liquor, and then separately collected in the tarry oil storage tank 19. Two separate tarry oil fractions may be collected where desired.

The collector mains 7 and 8 are operated 115 in much the usual manner except that the degree of cooling of the gases is regulated by control of the quantity of ammonia liquor sprayed into the gases. The collector main 6 is equipped in a novel fashion and is employed for the distillation of tar. The tar to be distilled is pumped from the tank 20 by the pump 20' thru the line 21 to sprays 21' in the main 6. This may be tar from any source supplied thru the line 22, or according to a preferred arrangement, this tar is the tar from the collector mains 7 120

and 8 and is supplied to the tank 20 from the tank 17 and may be supplied in a regulated amount.

The tar from the tank 20 is pumped into the collector main 6 and there distilled. The tar may advantageously be sprayed into the hot gases passing thru the collector main and for this purpose sprays 21' are positioned throughout the length of the main, much as ammonia liquor sprays are ordinarily placed. The main may also be equipped with agitating means which may comprise paddles such as the paddles 23 on the shaft 24. This shaft is adapted to be rotated at high speed by the motor 25.

Bearings to support the shaft 24 may be positioned at intervals along the collector main. Such bearings may be protected by suitable means from the spray of tar maintained in the main as, for example, by a housing such as that indicated at 26 in Fig. 3. The shaft may be supported by a bracket 27, in suitable bearings indicated at 28. The bracket and bearings may advantageously be separated on all sides from the collector main by the housing. In this case the shaft will pass thru the housing by means of suitable stuffing boxes. The bracket 27 is supported from outside of the main in any suitable manner.

Figs. 4 and 5 show modified forms of agitating means which may be employed instead of the paddles 23 on the shaft 24 for spraying the tar from the bottom of the collector main up into the gases. Vertical shafts such as those shown at 29 in Fig. 4, may be located at intervals along the collector main. The shafts may be driven by individual motors 30, or they may be driven from a common drive shaft. Agitating means such as the nest of cones indicated at 31 may be employed for spraying the tar into the gases. In this case the gases may be sprayed to a less extent than with the other devices illustrated due to the tendency of the cones to throw the spray horizontally from their upper edges. Fig. 5 shows a somewhat modified arrangement comprising the shaft 32 provided with paddles 33 and driven by the motor 34.

The tar, thrown up into the hot gases by any suitable agitating means, is distilled. The spray of tar produced within the main should be sufficient to keep the walls of the main washed down and to prevent the accumulation of pitch thereon, and sufficient tar should be circulated thru the main or agitation should be sufficiently violent to prevent the accumulation of hard deposits of pitch within the bottom of the main.

The pitch resulting from the distillation of the tar by the hot gases is drawn off thru the adjustable levelling arm 35 into the tank 36. The position of the levelling arm controls the depth of pitch maintained within

the collector main, and thus the extent to which the agitating means dips into the pitch within the main. The hot enriched gases resulting from the distillation of the tar in the main 6 pass over thru the cross-over main 10 to the condensers 13 and are combined with the gases passing over thru the cross-over mains 11 and 12 and together the gases are cooled in the condensers.

The gases passing over thru the cross-over main 10 are enriched in condensable constituents and if cooled would yield an oil of relatively low carbon content. By blending these gases passing thru the cross-over main 10 with gases passing over thru the cross-over mains 11 and 12, which latter gases have not been cleaned nor enriched in oil vapors, a gas is obtained which, on cooling, will yield a tarry oil, but the tarry oil will be of lower free carbon content than ordinarily owing to the lower free carbon content of the oils condensed from the enriched gases. By regulating the extent to which the gases passing thru the cross-over main 10 have been enriched, and the extent to which entrained impurities have been removed from the gases during the enriching operation, and the blending of these gases with the gases from 11 and 12 in regulated amount, the free carbon content of the tarry oil which is produced may be controlled.

Means for withdrawing a regulated portion of the gases from the mains 11 and 12 or for withdrawing a portion of the gases from the main 10 may be provided. For example, a portion of the enriched gases may be withdrawn thru the main 37 and collected in a different condensing system. Where the plant comprises additional ovens connected with one or more other gas collecting mains, by properly arranging the pressures within the mains gases may be drawn from these other mains thru the main 37 in regulated amount, and blended with the gases from the collector mains 6, 7 and 8 in such amount as to produce a tarry oil of desired properties in the condensers 13.

The sprays 38 are connected with a source of ammonia liquor thru the line 39. The temperature within the main 6, and hence the degree of distillation of tar within the main, can be regulated by spraying a limited amount of ammonia liquor into the gases in the main thru these sprays 38. By properly selecting the tar to be distilled within the collector main 6 and by regulating the distillation so that desired higher boiling oils are distilled from this tar, the boiling range of the tarry oil obtained from the condensers 13 may be controlled. By distilling a tar which is more or less free from lower boiling constituents as, for example, heavy tar from the collector mains 7 and 8, or employing a partially distilled tar and distilling the tar within the collector main 6

to produce a pitch of relatively high melting point, the oils carried by the gases thru the cross-over main 10 will be of high boiling range and a tarry oil of relatively high 5 boiling range will be collected in the condensers 13. Moreover, if the temperature maintained within the collector mains 7 and 8 is higher than usual as by reducing the amount of ammonia liquor sprayed into the 10 gases passing thru these mains, the tar withdrawn from these mains will be a heavier tar than usual and the gases passing thru the cross-over mains 11 and 12 will contain oils of higher boiling range than usual. By proper regulation of the temperatures employed in the collector mains 7 and 8 and regulation of the character of the tar fed to main 6 as well as the degree of the distillation within the main 6, a tarry 15 oil of higher boiling range may be obtained directly in the condensers 13, even where the cooling of the gases in this condenser is sufficient to produce a total condensate, as where the gases are cooled to a temperature 20 in the neighborhood of 45° C. or lower. The process may be so controlled that this tarry oil is of satisfactory boiling range for use directly as creosoting composition.

The distillation within the collector main 25 6 may be controlled to some extent by blending with the tar to be distilled some of the tarry oil from the tank 19 or other tarry oil containing lower boiling ingredients. Such tarry oil may be supplied thru the line 28 by means of the pump 29.

The enriched gases which do not contain as much entrained matter per unit of condensable constituents as the ordinary gases are blended with unenriched gases in the 30 proportion required to produce a tarry oil product of desired free carbon content. The properties of the tarry oil product may also be regulated by controlling the extent to which the gases are enriched, the tar employed for enriching the gases, the temperatures at which the enriched and unenriched gases leave the collector mains, the extent to which the gases are cooled in the condensers, etc. Likewise the number of 35 mains equipped for distillation may be varied to produce greater or smaller quantities of enriched gases than in the case described in which main 6 is so equipped and mains 7 and 8 are of the usual type.

55 I claim:

1. The method of producing tarry oil of regulated composition in the by-product recovery system of a coal distillation plant, which comprises collecting a portion of the 60 gases from the plant in a collector main while the gases are yet at an elevated temperature, continuously bringing a regulated quantity of tar into direct contact with the gases in the collector main at said temperature, said gases supplying all of the 65

heat required for distilling off volatile oils from the tar, thereby effecting continuous and regulated distillation of the tar to pitch and a regulated uniform enrichment of the gases in their content of condensable oils, 70 retaining condensable oils in the enriched gases, collecting another portion of the gases from the plant in a second collector main, blending the enriched gases while containing the condensable oils, with the gases from 75 said second collector main, and cooling the combined gases to produce tarry oil.

2. The method of producing a creosoting composition in the by-product recovery system of a coal distillation plant, which comprises collecting a portion of the gases from ovens or retorts of the plant in a gas collector main while the gases are yet at an elevated temperature, continuously bringing tar in regulated amount into direct contact with the gases in the collector main at said temperature, said gases supplying all of the heat required for distilling off the volatile oils from the tar thereby effecting continuous and regulated distillation of the tar to pitch and cleaning and uniform enrichment of the coal distillation gases in condensable oils, 80 retaining condensable oils in the enriched gases, collecting gases from another portion of the ovens or retorts of the plant 85 in a second collector main and subjecting them to regulated cooling therein to remove therefrom only a portion of the condensable constituents whereby a substantial portion of the condensable constituents is retained 90 in the gases in the vapor phase, combining the cleaned and enriched gases while containing the condensable oils, with the gases from the second collector main, and cooling the combined gases to separate therefrom 95 a creosoting composition.

In testimony whereof I affix my signature.
STUART PARMELEE MILLER.
